United States Patent Office.

SAMUEL VANSTONE, OF PROVIDENCE, RHODE ISLAND, ASSIGNOR TO HIMSELF AND JOHN STEWART, OF SAME PLACE.

Letters Patent No. 76,562, dated April 7, 1868.

IMPROVED CHAIN-LINK.

The Schedule referred to in these Letters Patent and making part of the same.

TO ALL WHOM IT MAY CONCERN:

Be it known that I, SAMUEL VANSTONE, of the city and county of Providence, in the State of Rhode Island, have invented a new and useful Improvement in Connecting-Links for Chains; and I do hereby declare that the following specification, taken in connection with the drawings, is a full, clear, and exact description thereof.

Figure 1 exhibits the two parts of the link placed in readiness to be united.

Figures 2 and 3 exhibit the respective halves.

The improvement described in the Letters Patent of the United States, No. 70,380, granted to myself and John Stewart, October 29, 1867, consists in making the two divisions of a connecting-link, with a central tongue, with chamfered ends, so that, when the two parts of the link are placed in their proper relation, the ends of such tongues will overlap and form a cross-bar. The method of constructing the link described in the patent referred to involves the use of a rivet to unite the overlapping ends of the tongues, and which rivet is the only means for preventing the two halves of the link from separating.

It does not always happen on shipboard, and in case of accidents, where the occasion for the use of this class of links most frequently arises, that a rivet is at hand, or if supplied, as it is intended to be with the link, that the tools requisite for closing it down are readily accessible.

It is the purpose, therefore, of the present invention to further improve this description of link by so constructing it that the two halves composing it can be more conveniently united together, and without danger of becoming easily separated.

In the accompanying drawings it will be seen that each division of the link is furnished, as in the case of the link described in the Letters Patent before referred to, with a central tongue, *a*. The ends of such tongues are chamfered, but on the opposite sides respectively on which they are chamfered in the instance shown in my previous invention, so that it is, in view of the dove-tail joints *b b* cut in the coinciding faces of the two divisions of the link, impossible to superpose over upon the other, as could readily be done were the overlapping ends of the tongues chamfered the opposite way. To enable, however, the two divisions to be brought together into their proper relation, one ear, *A*, of each division respectively is bent upward, as shown, when the article is manufactured, and in that condition should be so furnished for use. Such bending back of the ears, as will be readily understood, will enable the chamfered end of one of the tongues to be slipped under the chamfered end of the other, which otherwise could not be done, when, the two parts of the link being properly placed, a blow upon each of the ears, so bent up, will cause the dove-tail joints *b b* to lock, and the two parts of the link will be firmly united.

This method of construction is applicable to links made of malleable metal, but as such material ought always to be employed, this fact constitutes no important objection in comparison with the other advantages of convenience and strength which are secured.

What I claim as my invention, and desire to secure by Letters Patent, is—

Constructing the two divisions of a connecting-link, in the manner substantially as described, for the purposes specified.

SAMUEL VANSTONE.
